United States Patent Office.

SAMUEL KIME, OF McVEYTON, PENNSYLVANIA

Letters Patent No. 76,083, dated March 31, 1868.

IMPROVED SHAFT-BEARING OR MILLSTONE-BUSH.

The Schedule referred to in these Letters Patent and making part of the same.

TO ALL WHOM IT MAY CONCERN:

Be it known that I, SAMUEL KIME, of McVeytown, in the county of Mifflin, and State of Pennsylvania, have invented new and useful Improvements in Shaft-Bearings or Millstone-Bushes; and I do hereby declare that the following is a full, clear, and exact description thereof, which will enable those skilled in the art to make and use the same, reference being had to the accompanying drawings, forming part of this specification, in which—

Figure 1 is a vertical section of my improved bearing.

Figure 2 is a plan view of the same.

Similar letters of reference indicate corresponding parts.

This invention is designed more particularly for millstone spindles or shafts, but is equally applicable as friction-roller bearings for other shafting.

In the accompanying plate of drawings, A is the box containing the friction-rollers B and arms D on which the rollers are borne. Studs *a* are tapped into the arms D, and on these studs the friction-rollers B work, as shown. The arms D are cast or otherwise formed with thimbles *d*, the holes of which are produced down through the arms, in the manner shown, for the purpose of receiving the studs *e* which are tapped into the bottom plate of the box A, as shown. Thus the studs *e* and thimbles *d* form a species of hinge on which the arms D work, and by means of this hinge the roller of each arm is brought in the desired position when the spindle or shaft E is being adjusted to the vertical. A set-screw, *g*, screws into the arm D, as shown, so that its head shall abut against the wall of the box A, and by this set-screw the rollers are adjusted up to the spindle or shaft E when occasion shall require. Extending from the bottom of the box, and exterior to it, is a stuffing-box, H, in which a follower, G, works in the usual manner, to compress the packing around the spindle. The follower G is screwed up by means of nuts *i* and screw-threads on the studs *h*, which latter are tapped into the bottom of the box A, as shown. This stuffing-box is for the purpose of preventing the escape of the oil or other lubricant, and which is particularly desirable when this invention is used as a bush for a millstone spindle.

In practice, four rollers and arms are sufficient, and are, with the box, made of cast metal, as composition, brass, or cast iron; but the rollers may be of wood, cast iron, composition, or Babbitt metal. In some situations lignumvitae rollers would answer with satisfactory result.

In operation, the box is filled with oil, and the follower set up, so that the oil will not leak from the stuffing-box; and when so filled with oil and adjusted, the spindle will run for weeks, and even months, without requiring the millstone to be lifted, thereby obviating the necessity of performing the laborious and tedious drudgery of lifting the stone at short intervals of three or four days to "tram" or adjust the same.

By the use of the above invention as a millstone-bush, a set of mill-burrs may be run with one-third the power required with the millstone-bushes heretofore in use.

The set-screws may be provided with jam-nuts to hold them against the inside of the box more firmly.

I claim as new, and desire to secure by Letters Patent—

1. The arms D, hung at one end to studs *e*, and bearing at their opposite extremities the friction-rollers B, when said arms are provided with adjusting-screws *g* passing transversely through them, and adapted to rest against the inner face of the side of the box A, all constructed and operating as and for the purpose specified.
2. The stuffing-box H and follower G, substantially as shown and described, in combination with the box A containing the rollers B and hinged arms D, all substantially as shown and described, and for the purpose of being used as a millstone-bush, all as set forth.
3. The set-screw *g*, in combination with the hinged arms D, rollers B, box A, and stud *e*, substantially as shown and described, for the purpose of adjusting the rollers B, all as set forth.

SAMUEL KIME.
